(57) **CLAIM**

The ornamental design for a bench support, as shown and described.

DESCRIPTION

FIG. 1 is a perspective view of a bench support comprising our design;

FIG. 2 is a front perspective view of a bench support comprising our design;

FIG. 3 is a side view of a bench support comprising our design;

FIG. 4 is a rear view of a bench support comprising our design;

FIG. 5 is a front view of a bench support comprising our design;

FIG. 6 is a top view of a bench support comprising our design.

FIG. 7 is a bottom view of a bench support comprising our design; and,

FIG. 8 is a rear perspective view of a bench support comprising our design.

The broken line showing of the bench back, bench seat and second bench support in FIG. 1 is included for the purpose of illustrating environmental structure and forms no part of the claimed design.

1 Claim, 6 Drawing Sheets
